PHONOGRAPHIC APPARATUS

Frank E. Runge, Oaklyn, N. J., assignor to Radio Corporation of America, a corporation of Delaware

Application May 31, 1940, Serial No. 337,994

16 Claims. (Cl. 274—1)

This invention relates to phonographic apparatus, and more particularly to the carriage mechanism for supporting the cutter head in recording machines of the type adapted to record sound upon a blank disk for immediate playback.

The primary object of my present invention is to provide a novel cutter carriage mechanism for disk recorders which will incorporate general improvements as to operation and handling.

More particularly, it is an object of my present invention to provide an improved, compact and foolproof carriage mechanism which may be controlled in such a manner that the careless dropping of the stylus or cutting needle on the record blank is practically impossible, whereby danger of ruining the blank from this cause is avoided.

Another object of my present invention is to provide improved cutter carriage mechanism and feeding means therefor for feeding the cutter head across the record blank which will be subject to much less wear than is characteristic of cutter feed mechanisms heretofore known.

Still another object of my present invention is to provide an improved cutter head supporting carriage which may be easily manipulated by the user either to bring it into engagement with the record blank or to disengage it from the record blank and which will remain in any position of adjustment, within predetermined limits, to which the carriage mechanism may be brought.

A further object of my present invention is to provide an improved cutter head supporting mechanism which will be automatically locked in suspended position and will not fall down onto the record blank when raised to this position.

Another object of my present invention is to provide an improved feed mechanism for the cutter head which will act in a positive manner and will not allow free movement of the carriage supporting the cutter head unless the stylus thereof is first removed from the record blank.

It is also an object of my present invention to provide improved cutter head feed mechanism as aforesaid by means of which it is possible to utilize the maximum available recording area on the blank.

Still a further object of my present invention is to provide an improved cutter head mounting by means of which the cutter head can be quickly and easily adjusted on its carriage to insure a proper angular relation between the cutting stylus and the surface of the record blank.

According to this invention, I mount a cylindrical supporting member on a pair of parallel guide rods for sliding movement thereon and rotatably mount on the supporting member a mounting member which pivotally supports the cutter head. Preferably, the cutter head is so mounted on its carriage that it may be adjusted

angularly thereon about the tip of its stylus as a center, whereby accurate adjustment of the needle with respect to the record blank may be obtained to thereby insure the proper cutting angle. The mounting member is comprised of two end-members which pivotally support the cutter head carriage and an intermediate member which is rotatable on said supporting member relative to said end-members. A handle carried by said intermediate member and extending radially outwardly therefrom affords means by which the mounting member may be manipulated on the supporting member. The mounting member and the cutter head are movable as a unit on the supporting member when the cutter head is raised from the record, and an "over-riding" clutch spring interposed between the supporting member and the mounting member is effective to hold the aforesaid unit in any position of adjustment and to prevent lowering of the cutter onto the record unless the handle is manipulated to turn the aforementioned intermediate member in a manner to release the clutch spring from locking relation with the supporting member.

For driving the cutter head across the record blank, I provide a lead screw which passes through the supporting member and which constitutes the driving element for a gear carried by the supporting member and constantly in mesh with the lead screw. A suitable friction clutch, also within the supporting member, is arranged to uncouple the supporting member (and therefore the aforementioned unit) from the driven gear as soon as the cutter head is raised from the record and to recouple the supporting member to said gear when the cutter head is lowered down onto the record blank. Since the driving element and the driven element are constantly in mesh when the cutter head is disengaged from the record and subsequently returned into engagement with the record, the stylus may be brought back on exactly the same radius of the record as that from which it was removed. I also provide the aforementioned intermediate member of the mounting device and the cutter head supporting carriage with cooperative means whereby the cutter head is first raised slightly from the record prior to raising the whole aforesaid unit to inoperative position and whereby, when said unit is brought back down into operative position, it comes to rest slightly in advance of engagement of the stylus with the record blank. Also, the control means for the aforementioned friction clutch is so related to the means for initially raising the cutter head from the record that the clutch is rendered operative to connect the supporting member to the driven gear just prior to engagement of the stylus with the record when the cutter is lowered thereonto.

The novel features which I consider characteristic of my invention are set forth with particularity in the appended claims. The invention itself, however, both as to its organization and method of operation, as well as additional objects and advantages thereof, will best be understood from the following description of one embodiment thereof when read in connection with the accompanying drawings, wherein

Figure 1 is an end elevation of my improved cutter carriage supporting mechanism with the guide rods and lead screw shown in section and with the cutter head shown in operative position on a record blank.

Figure 2 is a sectional view thereof taken substantially along the line II--II of Figure 1.

Figure 3 is a fragmentary sectional view taken on the line III--III of Figure 1.

Figure 4 is a view similar to Figure 1 but showing the cutter head raised to inoperative position.

Figure 5 is an exploded perspective view of the supporting member, the intermediate member of the carriage supporting mounting, and the clutch locking spring therebetween, and

Figure 6 is a detail perspective view of the clutch device for coupling and uncoupling the cutter from the feed mechanism therefor.

Referring more particularly to the drawings, wherein similar reference characters designate corresponding parts throughout, there is shown a pair of parallel guide rods 1 and 3 upon which is slidably mounted for longitudinal movement a supporting member 5 of cylindrical exterior form and provided with a shelf 7 and a pair of journal bearings 9 and 11 in which the guide rods 1 and 3, respectively, are received, the bearing members 9 and 11 extending beyond the ends of the member 5. The supporting member 5 is also formed with a stepped wall 13 which is provided with a pair of openings 15 and 17, the member 5 being otherwise of hollow construction and the opening 17 being sufficiently large to receive a rotatably mounted lead screw 19 which may be rotated in any suitable manner well known in the art and which constitutes a driving member, as will be presently described in greater detail. It will be apparent from the description thus far that the supporting member 5 is slidable on the guide rods 1 and 3 longitudinally along the lead screw 19 and that the lead screw 19, supported in suitable journal bearings (not shown), is rotatable relative to the supporting member 5 within the opening 17 of the wall 13.

Rotatably mounted on the exterior, cylindrical surface of the supporting member 5 is a cutter head mounting generally designated as 20 and constituted by a pair of end-members 21 and an intermediate member 23, the end-members 21 each being provided with a downwardly extending arm 25 and being connected together at the arms 25 by means of a screw 27 and at the top by means of a cross-piece or plate 29 and screws 31. Longitudinal movement of the mounting 20 on the supporting member 5 is prevented by engagement of inwardly directed flanges 21a of the end pieces 21 with the ends of the supporting member 5. Although the whole mounting 20 is rotatable on the supporting member 5 as a unit, the intermediate member 23 is itself movable on the mounting 20 relative to the end-members 21 for a purpose to be presently set forth in greater detail.

Pivotedly mounted on conically tipped bearing pins 33 which are carried by the arms 25 is a

carriage 35 having a rearwardly and upwardly extending arm 37 terminating in a toe 39, a forwardly and upwardly extending arm 41 provided with a pair of screws and nuts 43, and also a forward extension 45. Secured to the back of a cutter head or other suitable sound translating device 47 which carries a stylus 49 is a rearwardly and downwardly extending bracket 51 formed with an arcuate slot 53 which has as its center the tip of the stylus 49. By loosening the screws and nuts 43, which pass through the arcuate slot 53, the bracket 51 may be adjusted on the arm 41 about the tip of the stylus 49 to provide the proper angular relation between the stylus 49 and a record blank R supported on a turntable T and with which the stylus 49 is in engagement in operative position. A coil spring 55 having one end fixed to the extension 45 of the carriage 35 and its other end secured to an adjusting screw 57 received in a bracket 59 on one of the members 21 and manipulated by means of a thumb-nut 61 serves to counter-balance the weight of the cutter head 47 and the carriage 35. By adjustment of the thumb nut 61, the depth of cut of the stylus 49 in the record blank R may also be controlled.

Rotatably mounted on the shelf 7 of the supporting member 5, as by means of a floating pin 63 having an enlarged head, and in constant mesh with the lead screw 19, is a gear 65 which is constantly driven by the lead screw 19, the lower end of the pin 63 being received in an enlarged opening 66 in the plate 7 to permit the pin 63 to float somewhat (see Fig. 3). A resilient clutch element 67 shaped substantially as shown in Figure 6 and comprising a back wall 67a, a vertical wide wall 67b bent forwardly from the back wall 67a, and a horizontal plate 67c also bent forwardly from the back wall 67a is secured to the wall 13 of the supporting member 5, as by means of a screw 69 passing through the wall 67b and threaded into the opening 15. The horizontal plate 67c of the clutch member 67 extends over the top surface of the gear 65, as clearly shown in Figs. 1, 3 and 4, a friction washer 68 being preferably interposed between the plate 67c and the top surface of the gear 65, and a second friction washer 70 being preferably interposed between the lower surface of the gear 65 and the shelf 7. The resilience of the clutch member 67 causes it to constantly force the pin 63 in the direction of the arrow A of Fig. 6 about the side wall 67b, thereby holding the gear 65 firmly in mesh with the lead screw 19.

As soon as power is supplied to the lead screw 19, it begins to rotate in its bearings and immediately drives the gear 65 to cause it to rotate on its shaft or pin 63. The clutch member 67, being formed of resilient material, is also so biased that the plate 67c thereof tends to move out of contact with the friction washer 68, so that normally rotation of the gear 65 does not serve to transmit power to the supporting member 5 through the clutch 67. When, however, sufficient pressure is applied to the plate 67c to press it firmly against the friction washer 68 and the gear 65, it is obvious that a coupling will be provided between the gear 65 and the supporting member 5 to cause the supporting member 5 and the parts carried thereby to move longitudinally along the guide rods 1 and 3 and the lead screw 19, whereby to feed the cutter head 47 radially across the record blank R. For this purpose, there is provided in the supporting member 5 a bore 71 into which the enlarged head of the pin

63 extends and in which are carried a coil spring 73 resting on the head of the pin 63 and a ball element 75 resting on the upper end of the coil spring 73. The intermediate member 23 of the mounting 20 is provided on its inner surface with a circumferentially extending recess or relief 77 which tapers off at its ends and into which the spring 73 is adapted to press the ball 75 when the intermediate member 23 is rotated on the supporting member 5, as by means of a handle 79 which may be threadedly received in an opening 81 in the member 23. When the cutter head 47 is in the operative position shown in Figure 1, the recess 77 is located somewhat to the left of the ball 75 and the spring 73 is compressed by reason of the engagement of the ball 75 with the inner surface of the member 23. As soon, however, as the handle is raised toward the position shown in Figure 4, the intermediate member 23 is rotated on the supporting member 5 relative to the end members 21 and the ball 75 slips into the recess 77 under the influence of the spring 73, whereby pressure is relieved from the clutch plate 61c. Consequently, although the gear 65 will continue to rotate, no power will be transferred therefrom through the clutch 67 to the supporting member 5, and therefore the supporting member and the parts carried thereby will cease movement along the guide rods 1 and 3 and the lead screw 19. Upon returning the handle 79 to the position of Fig. 1, the reverse action will, of course, take place and the supporting member 5 will again be coupled to the gear 65 to resume movement of the cutter head 47 radially across the record blank R.

The intermediate member 23 of the mounting 20 is also provided with a circumferentially extending slot 83 into which the toe 39 may extend and in which is carried a roller 85 rotatably supported on a rod 87 which extends through openings 89 in the member 23. At one end, the member 23 is cut away longitudinally and circumferentially to form a recess 91 terminating in shoulders 93 and 95. At its opposite end, the member 23 is recessed diametrically and circumferentially to provide an annular recessed portion 97 having a somewhat larger diameter than the remaining portion of the member 23. The latter end of the member 23 is also provided with a longitudinal recess 98 terminating in shoulders 99 and 101. A coil spring 103, having its ends 105 and 107 turned substantially radially outwardly, is received in the recessed portion 97 and is therefore interposed between the portion 97 of the intermediate member 23 and the external surface of the supporting member 5. The inside diameter of the coil 103 is slightly smaller than the external diameter of the supporting member 5, so that the spring 103 normally grips or hugs the member 5, and its outside diameter is less than the inside diameter of the recess 97. The ends 105 and 107 of the spring 103 extend through the recess 98 with the end 105 thereof occupying a position adjacent the shoulder 99 and the end 107 thereof, which is somewhat longer than the end 105, occupying a position adjacent the shoulder 101.

In the operating position of the cutter head 47, as shown in Figure 1, the handle 79 is in lowered position, and the shoulder 93 of the intermediate member 23 and the cross bar or plate 29 connecting the end members 21 of the mounting 20 are in engagement with a stop pin 109 threaded into an opening 111 in the supporting member 5. At this time, the roller 85 is slightly spaced from the toe 39, as clearly shown in Fig. 1. 70 75

When the handle 79 is raised toward the position shown in Figure 4, the intermediate member 23 of the mounting 20 immediately begins to rotate on the supporting member 5 and the relief or recess 77 is brought over the ball 75. Just prior to this, the play between the roller 85 and the toe 39 has been taken up and the roller 85 acts upon the toe 39 to cam the carriage 35 clockwise about its pivots 33 to thereby disengage and slightly raise the stylus 49 from the record blank R. Since the ball 75 is now in the recess 77 and pressure on the clutch plate 61c has been relieved, the coupling between the driven gear 65 and the supporting member 5 is broken, and the carriage mounting will no longer move longitudinally along the lead screw 69 in response thereto, notwithstanding the fact that the gear 65 continues to rotate. Movement of the handle 79 upwardly causes almost immediate engagement of the shoulder 101 of the member 23 with the end 107 of the spring 103 and continued movement of the member 23 thereafter causes the spring 103 to tend to unwind and thereby relieve its grip from the supporting member 5 so that the mounting member 20 thereafter is free to rotate without binding on the supporting member 5. Continued rotation of the intermediate member 23 in a clockwise direction, as viewed in Figures 1 and 4, will cause the short end 105 of the spring 103 to slip under the cross piece 29 and the long end 107 thereof to catch up with and engage the cross-piece 29. Thus, rotation of the end-members 21 and the intermediate member 23 of the mounting 20, the carriage 35, and the cutter head 47, all as a unit, will be effected, whereby the cutter head 47 may be raised to a point remote from the record blank R, as shown in Figure 4. Movement of the aforementioned unit in a clockwise direction, as shown in Figures 1 and 4, is limited by engagement of the shoulder 99 of the member 23 with the stop pin 109. If the handle 79 is stopped within the limits of movement afforded by the shoulders 93 and 95 in cooperation with the stop pin 109, the spring 103 will immediately contract again to grip the supporting member 5 with sufficient force to releasably lock the assembly in the adjusted position, so that there is no danger of the cutter head falling back down onto the record blank and causing injury to either the blank R, the stylus 49, or both.

Upon return, or counter-clockwise, movement of the handle 79, as viewed in Figures 1 and 4, the shoulder 99 engages the adjacent end 105 of the spring 103 and again, therefore, tends to unwind the spring 103. It will be noted that even in the fully raised position of the cutter head shown in Figure 4, the arms 26 are located below the horizontal diameter passing through the center of the supporting member 5. Consequently, as the handle 79 is returned toward the lowered position of Fig. 1, the assembly constituted by the end members 21 of the mounting 20, the carriage 35 and the cutter head 47 will follow the intermediate member 23 of the mounting 20 under the influence of gravity, and this action will continue until the cross-piece or plate 29 has engaged the stop pin 109, whereupon further counter-clockwise rotation of the end members 21 will be prevented. The stylus 49 will not, however, be in engagement with the record blank R at this time because the roller 85 will still be in engagement with the toe 39. Also, the ball 75 will still be in the recess 77 and the supporting member 5 will not be clutched to the driven gear 65.

Immediately after the cross-piece 29 has engaged the stop pin 109, continued downward movement of the handle 79 will move the intermediate member 23 to a position such that the adjacent bevelled end of the recess 11 will apply pressure to the ball 15 and the spring 13 will be compressed to force the clutch plate 67c into engagement with the friction washer 68 and the gear 65. At this time, the roller 85 is still in engagement with the toe 39, and immediately after the clutch plate 67c has been engaged firmly with the gear 65, the roller 85, receding from the toe 39, will permit the gradual lowering of the cutter head 47 to cause the cutting stylus to gently engage the record blank, after which the roller 85 moves out of engagement with the toe 39 and the handle 79 will come to rest by reason of the engagement of the shoulder 93 against the stop pin 109. Thus, radial movement of the cutter head 47 across the record blank R will commence at substantially the same instant that the stylus 49 is brought into engagement with the record blank and no loss of the recording area on the record blank will result.

From the foregoing description, it will be apparent to those skilled in the art that I have provided an improved cutter carriage mechanism which is positive in action and which incorporates a number of novel features. By having the gear 65 constantly in engagement with the lead screw 19, longer life of the mechanism is assured by reason of the fact that each portion of the gear 65 suffers less wear than does the conventional half-nut follower of the prior art mechanisms. Moreover, there is never any clashing of gears with my improved arrangement because the gear 65 and the lead screw 19 are never out of mesh. In addition, it will be obvious that it is possible, with my improved cutter carriage mechanism, to pick up or resume recording at substantially the point where it was last left upon returning the stylus 49 to operative position after first having been removed from the record blank, depending upon the skill of the operator.

Although I have shown and described but one embodiment of my invention, it will be apparent to those skilled in the art that many other modifications, as well as changes in the one herein described, are possible. I therefore desire that my invention shall not be limited except insofar as is made necessary by the prior art and by the spirit of the appended claims.

I claim as my invention:

1. In phonographic apparatus, the combination of guide means, a supporting member slidably carried on said guide means, a mounting rotatable on said supporting member, and a sound translating device pivotally carried by said mounting, said sound translating device being pivotally movable on said mounting relative to said supporting member and being rotatable as a unit with said mounting on said supporting member.

2. In phonographic apparatus, the combination of guide means, a supporting member slidably carried on said guide means, a mounting rotatable on said supporting member, a sound translating device pivotally carried by said mounting and adapted to have cooperative engagement with a record, means on said mounting cooperatively associated with said sound translating device for effecting initial movement of said sound translating device on said mounting to effect disengagement of said device from the

record, and manually operable means on said mounting for thereafter rotating said sound translating device and said mounting as a unit on said supporting means to remove said device from adjacent the record to a point relatively remote therefrom.

3. In phonographic apparatus, the combination of guide means, a supporting member slidably carried on said guide means, a mounting rotatable on said supporting member, a sound translating device pivotally carried by said mounting and adapted to have cooperative engagement with a record, means on said mounting cooperatively associated with said sound translating device for effecting initial movement of said sound translating device on said mounting to effect disengagement of said device from the record, manually operable means on said mounting for thereafter rotating said sound translating device and said mounting as a unit on said supporting means to remove said device from adjacent the record to a point relatively remote therefrom, and means for releasably holding said unit in any selected position on said supporting member.

4. In phonographic apparatus, the combination of guide means, a supporting member slidably carried on said guide means, a mounting rotatable on said supporting member, a sound translating device pivotally carried by said mounting and adapted to have cooperative engagement with a record, means on said mounting cooperatively associated with said sound translating device for effecting initial movement of said sound translating device on said mounting to effect disengagement of said device from the record, manually operable means on said mounting for thereafter rotating said sound translating device and said mounting as a unit on said supporting means to remove said device from adjacent the record to a point relatively remote therefrom, and a spring clutch interposed between said supporting member and said mounting for releasably holding said unit in any pre-selected position on said supporting member.

5. In phonographic apparatus, the combination of guide means, a supporting member slidably carried on said guide means, a mounting rotatable on said supporting member, a carriage pivotally carried by said mounting, a sound translating device carried by said carriage and adapted to have cooperative engagement with a record, said mounting including relatively movable members one of which includes means for actuating said carriage to raise said sound translating device slightly from the record upon initial movement of said last named member on said supporting member, and means for thereafter effecting movement of said mounting, said carriage and said sound translating device as a unit to remove said sound translating device from adjacent the record to a point remote therefrom.

6. The invention set forth in claim 5 characterized by the addition of a spring clutch interposed between said mounting and said supporting member for releasably holding said unit in any pre-selected position on said supporting member.

7. The invention set forth in claim 5 characterized in that said mounting has an annular recess therein terminating in circumferentially spaced shoulders, and characterized further by the addition of a coil spring within said recess,

said spring being normally wound snugly around and in gripping engagement with said supporting member on a diameter slightly smaller than the diameter of said recess and having its ends offset for engagement with one or the other of said shoulders whereby, when said mounting is rotated on said supporting member, one or the other of said shoulders engages the adjacent of said offset ends to slightly expand said spring and loosen said spring from said supporting member to permit free rotation of said unit on said supporting member, said spring contracting again when rotation of said unit on said supporting member has ceased to thereby again grip said supporting member and releasably lock said unit in the position to which it has been moved.

8. The invention set forth in claim 5 characterized by the addition of cooperative means on said supporting member and on said mounting for limiting the rotation of said mounting on said supporting member.

9. The invention set forth in claim 5 characterized in that said mounting comprises a pair of end members coupled together for unitary movement, said end members pivotally carrying said carriage, and an intermediate member rotatable on said supporting member relative to said end members, said intermediate member including the means for actuating said carriage, characterized further in that said intermediate member is provided with a recess terminating in a pair of circumferentially spaced shoulders, and characterized further by the addition of a stop pin on said supporting member extending through said recess for engagement by said shoulders to limit the rotation of said mounting on said supporting member.

10. In phonographic apparatus, the combination of a driving member, a driven member associated therewith, a sound translating device, and clutch means for either coupling said device to or uncoupling said device from said driven member at will.

11. In phonographic apparatus, the combination of a driving member, a driven member in constant driving engagement with said driving member, a sound translating device, and clutch means for either coupling said device to or uncoupling said device from said driven member whereby to either effect or break driving engagement between said driving member and said device at will.

12. In phonographic apparatus, the combination of a lead screw constituting a driving member, a gear in constant engagement with said lead screw and adapted to be driven thereby, a sound translating device, and clutch means for either coupling said device to or uncoupling said device from said gear whereby to either effect or break driving engagement between said lead screw and said device at will.

13. In phonographic apparatus, the combination of guide means, a supporting member slidably carried on said guide means, a mounting rotatable on said supporting member, a sound translating device carried by said mounting, a rotatable lead screw extending through said supporting member and constituting a driving member, said supporting member, mounting and sound translating device being movable as a unit on said guide means longitudinally along said

lead screw, a gear, carried by said supporting member, said gear being in constant mesh with said lead screw and being driven thereby, and clutch means carried by said supporting member for either coupling said supporting member to or uncoupling said supporting member from said gear whereby to either effect driving engagement between said lead screw and said supporting member to cause said unit to move along said guide means, or to break driving engagement between said lead screw and said supporting member to permit rotation of said lead screw independently of said unit.

14. In phonographic apparatus, the combination of guide means, a supporting member slidably carried on said guide means, a mounting rotatable on said supporting member, a sound translating device pivotally carried by said mounting and adapted to have cooperative engagement with a record, means for moving said sound translating device into or out of engagement with the record at will, a rotatable lead screw extending through said supporting member and constituting a driving member, said supporting member, mounting and sound translating device being movable as a unit on said guide means longitudinally along said lead screw, a gear carried by said supporting member, said gear being in constant mesh with said lead screw and being driven thereby, and a clutch carried by said supporting member for either coupling said supporting member to or uncoupling said supporting member from said gear at will whereby to control the driving coupling between said unit and said lead screw, said second named means including a portion associated with said clutch and arranged to uncouple said supporting member from said gear when said device is disengaged from the record and to couple said supporting member to said gear when said device is brought into engagement with the record.

15. The invention set forth in claim 14 characterized in that said mounting includes a pair of end members which pivotally carry said sound translating device and an intermediate member rotatable on said supporting member relative to said end members, characterized further in that said intermediate member is provided with a relief, characterized further in that said supporting member is provided with a bore, characterized further by the addition of a compression coil spring in said bore and a ball element supported by said coil spring, and characterized still further in that said clutch comprises a resilient element fixed to said supporting member and having a surface adapted to lie against a face of said gear, said coil spring being arranged to normally press said element against said gear to frictionally couple said element to said gear, and said relief being so located in said intermediate member that, upon rotation thereof on said supporting member in a predetermined direction, said ball will be forced thereinto whereby to relieve the compression on said coil spring and thereby relieve the pressure of said element against said gear.

16. In phonographic apparatus, the combination of a carriage, a sound translating device including a stylus, and means for adjustably mounting said device on said carriage for angular adjustment of said device about the tip of said stylus as a center.
